UNITED STATES PATENT OFFICE.

CHARLES G. HARVEY, OF DEVILS LAKE, NORTH DAKOTA.

SPARK-PLUG.

1,232,303.

Specification of Letters Patent.

Patented July 3, 1917.

Application filed May 27, 1913. Serial No. 770,918.

To all whom it may concern:

Be it known that I, CHARLES G. HARVEY, (who have declared my intention to become a citizen of the United States,) residing at 5 Devils Lake, in the county of Ramsey and State of North Dakota, have invented new and useful Improvements in Spark-Plugs, of which the following is a specification.

The invention relates to spark plugs for 10 use in connection with electric ignition systems for internal combustion engines and provides a plug of the breech type, whereby the plug proper with its electrode may be removed quickly from the body or shell 15 without requiring the detachment of such body from the engine and which usually cannot be easily effected.

The invention provides a spark plug embodying inner and outer shells, the latter 20 constituting the body and being screwed into the head of the cylinder and the inner shell carrying the plug and having detachable connection with the outer shell by means of a bayonet joint.

25 The invention consists of the novel features, details of construction and combination of parts, which hereinafter will be more particularly set forth, illustrated in the accompanying drawing, and pointed out in 30 the appended claim.

Referring to the drawing, forming a part of the specification,

Figure 1 is a perspective view of a spark plug embodying the invention.

35 Fig. 2 is a vertical central section.

Fig. 3 is a detail view of the inner shell.

Fig. 4 is a view of the plug proper.

Fig. 5 is a top plan view of the inner shell, showing the spanner in operative position.

40 Corresponding and like parts are referred to in the following description, and indicated in all the views of the drawing, by the same reference characters.

45 The numeral 1 designates the body or outer shell, which is provided at its upper end with a polygonal portion to receive a wrench or other tool by means of which such body or shell is screwed into or out from 50 the head of the cylinder, the lower portion of such body or shell being externally threaded to make screw connection with the cylinder. The body 1 has its lower portion contracted and its lower end further reduced 55 to receive the small end of the plug 2. Lugs 3 project inward from the sides of the shell

and are preferably located at diametrically opposite points. The inner shell comprises a body 4 and head 5, the latter being of larger diameter than the body 4 and comprising an upstanding flange in the upper edge of which are formed notches 6 to receive the engaging ends of a spanner 7 by means of which the inner shell is turned either to tighten or loosen the same. Bayonet slots 8 are formed in opposite sides of the body 4 and are adapted to receive the lugs 3, such parts constituting bayonet joints, whereby the inner shell is secured within the outer shell when the parts are 60 assembled. The head 5 is adapted to overlap the upper end of the body or outer shell 1. An inner flange 9 is formed at the lower end of the body 4 and engages a shoulder 10 of the plug 11, thereby limiting the inward movement of such plug. A sleeve 12 engages the shoulder 10 and makes connection with the inner shell, thereby retaining the plug 11 in position. The sleeve 12 may be secured to the inner shell either frictionally or in any positive manner.

75 The plug 11 may be of porcelain or other insulating material commonly employed in devices of this nature and is formed with a central opening in which is fitted an electrode 13, said electrode projecting beyond opposite ends of the plug. When the plug is in position the lower end of the electrode 13, which is enlarged, is spaced slightly from the lower end of the body or shell 1 80 so as to provide a gap for the passage of the spark.

85 The plug 11 being secured within the inner shell the latter is adapted to be detachably connected with the outer shell or body by means of the bayonet joints, the lugs 3 passing through the vertical slots and thence into the inclined slots of the parts 8, the inner shell being made secure by turning the same to cause the lugs 3 to 90 ride upon the inclined edges of the bayonet slots in a manner well understood. When it is required to remove the plug the inner shell is turned by means of the spanner 7 to bring the lugs in register with the vertical slots when the inner shell, together with the plug, may be easily withdrawn from the body or outer shell.

105 110 From the foregoing description, taken in connection with the accompanying drawing, the advantages of the construction and of the method of operation will be readily ap-

2
parent to those skilled in the art to which the invention appertains, and while I have described the principle of operation of the invention, together with the device which 5 I now consider to be the best embodiment thereof, I desire to have it understood that the device shown is merely illustrative, and that such changes may be made when desired as are within the scope of the claim 10 appended hereto.

Having thus described the invention what is claimed as new, is—

15 The combination with a spark plug of an outer shell provided with a threaded engaging end, inwardly projecting lugs carried

by said outer shell, a removable inner shell provided with bayonet slots for engagement with the lugs of the outer shell, an outwardly projecting annular flange formed on said inner shell, and overlapping the upper 20 edge of the outer shell and a frictionally engaged lining for said inner shell, said lining forming a rear closed removable wall for the bayonet slots.

In testimony whereof I affix my signature in presence of two witnesses.

CHARLES G. HARVEY.
